UNITED STATES PATENT OFFICE.

CLARENCE R. WELCH, OF DENVER, COLORADO.

PNEUMATIC ROCK-DRILL.

1,391,708.

Specification of Letters Patent. Patented Sept. 27, 1921.

Application filed February 14, 1920. Serial No. 358,584.

To all whom it may concern:

Be it known that I, CLARENCE R. WELCH, a citizen of the United States, residing at the city and county of Denver and State of Colorado, have invented certain new and useful Improvements in Pneumatic Rock-Drills; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The object of this invention is to provide a drill which is simple in construction and efficient in operation.

Briefly, the invention comprises a casing containing a pneumatically operated hammer, and a double cam, one face of which is adapted to retract the hammer and the other face to operate a reciprocable rod whose forward end has a cam face controlling a block bearing a ratchet which rotates the drill.

25 In the drawings:

Figure 1 is a longitudinal section through the device, as indicated by line 1—1 of Fig. 2.

Fig. 2 is a cross section taken on the line 30 2—2 of Fig. 1, but showing the mechanism rotated ninety degrees to the right from the position of Fig. 1.

The operating parts are housed in a casing 10 whose rear end plate 12 is provided 35 with a fitting 14 for supplying air under pressure. The hammer 16 is journaled at both of its ends in the casing, and its rear end is provided with an air chamber 18. Journaled upon the middle portion of the 40 hammer 16 is a double-faced cam 20. One face 22 terminates at an abrupt wall 24, and this face 22 is adapted to engage a roller 26 on a projecting tongue 28, which is guided by a longitudinally extending rod 29. Opposite to the cam face 22 a bearing face 32 is provided, which travels upon rollers 30 mounted in the casing 10, and adapted to take the thrust of said cam member 20. A gear 34 is fixed upon the cam member 20 45 and is driven by a pinion 36 on a shaft 38 of an electric motor 40 mounted upon the casing 10.

On the side of the cam member 20, opposite from the cam face 22, a second cam face 50 42 is provided. This is adapted to engage

a projection 44 on a reciprocating rod 46, which has at its forward end an offset 48, having an inclined or beveled cam face 50. The cam 42 of the member 20 moves the rod 46 against the tension of a spring 51, which 55 spring 51 returns the rod 46 when freed by the cam 42. The cam face 50 of the rod 46 engages a corresponding face of a block 52, which is urged against said face 50 by means of a spring 54. The block 52 is provided 60 with a slot 56, in which there is mounted a spring-pressed dog 58, which is adapted to engage in teeth formed on a ratchet 60, which rotates the chuck or holder for the 65 drill steel 62.

In operation, the motor 40, through the medium of the gear 34, rotates the cam member 20 upon the hammer 16, which is continually under air pressure in the chamber 18. When the cam face 22 frees the 70 roller 26, the pressure propels the hammer 16 forwardly into engagement with the end of the drill steel 62. As the cam member 20 rotates, the face 14 urges the rod 46 forwardly against the tension of spring 51. 75 During this operation the cam face 50 of the rod 46 bears upon the inclined face of the block 52, thus urging said block 52 away from said rod 46, against the tension of the 80 spring 54. This causes the dog 58 to rotate 85 the ratchet 60, and thereby the drill steel 62.

Water may be supplied to the steel 62 by means of a tube 64, extending through the casing and accommodated in a slot 66 in the hammer 16.

I claim:

1. In a rock drill, a casing, a hammer reciprocable therein, a drill to be engaged by said hammer, a rotary cam, about the hammer, a gear on the cam to turn the same, 90 means operated by the cam to turn the drill, and pneumatic means to propel the hammer.

2. In a rock drill, a casing, a hammer reciprocable therein, a drill steel to be engaged by said hammer, a rotary cam, a reciprocable rod adapted to be engaged and operated by said cam, a ratchet to turn said drill, a block having a dog to engage said ratchet, and a cam on said reciprocable rod 100 to move said block for the purpose of rotating said ratchet.

3. In a rock drill, a casing, a hammer reciprocable therein, a drill to be engaged by said hammer, a rotary cam, a reciprocable 110

rod directly engaged by said cam, a cam on said rod, and means operable by the last mentioned cam to rotate said drill.

4. In a rock drill, a casing, a hammer reciprocable therein, a hollow cam member positioned about said hammer, means to rotate said cam member, said cam member having a face to retract the hammer, said cam having a second face, a rod movable by said second face, a drill adapted to be engaged by said hammer, and an operative connection between said rod and said drill to rotate the drill.

5. In a rock drill, a casing, a hammer reciprocable therein, a cam member journaled on the hammer, means to rotate said cam member, a drill, a reciprocable rod, and a

connection between said rod and said drill to rotate the drill, said cam member having a face to engage and retract said hammer and a second face to engage and move said rod.

6. In a rock drill, a casing, a hammer reciprocable therein, a cam member journaled on the hammer, means to rotate said cam member, a drill, a reciprocable rod, and a connection between said rod and said drill to rotate the drill, said cam member having a face to engage and retract said hammer and a second face to engage and move said rod, said hammer having an air chamber in the rear thereof for receiving air under pressure to propel the hammer.

In testimony whereof I affix my signature.
CLARENCE R. WELCH.
